HANS GERDIEN, OF BERLIN-SCHMARGENDORF, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

MEANS FOR TRANSMITTING SIGNALS FOR WIRELESS TELEGRAPHY.

Application filed November 30, 1921. Serial No. 518,846.

To all whom it may concern:

Be it known that I, HANS GERDIEN, a citizen of the German Empire, residing at Berlin-Schmargendorf, Germany, have invented certain new and useful Improvements in Means for Transmitting Signals for Wireless Telegraphy, of which the following is a specification.

In the transmission of Morse signals for wireless telegraphy, the interruption of the antenna energy is connected with difficulties owing to its high voltage. Thus, it is more preferable to untune the antenna when the signals cease, so that it ceases to take-up energy. For the purpose of untuning the antenna in a simple manner, it is fitted with a self-induction having an iron core. The amount of self-induction is changed by a change of the saturation of the iron, which can be easily attained by continuous current of ordinary voltage. The antenna is, for instance, tuned if the iron core is excited by the continuous current field, and untuned if the continuous current field disappears. To transmit a Morse signal, thus, a continuous current need to be sent only through a separate winding of the self-induction coil.

According to the present invention, an increased voltage is temporarily used for the excitation of said continuous current field. Thereby, a quicker formation of the continuous current field and thus sharp signals are obtained. Correspondingly, the vanishing of the field can be artificially accelerated. Such and similar means for a quick excitation and dissipation of continuous current fields are already known in the art in connection with other branches of the electro-technical industry, for instance with dynamos and electromotors. For the transmission of signals for wireless telegraphy, said means have the particular advantage that the signals can be quickly started with full energy and again sharply cut off, which is of great importance for a good understanding at large distances. By the improvement according to the present invention, besides, the utilization of radio-telegraphic plants is considerably increased, for the quicker the antenna is fully energized at the start of a signal, the shorter

may be the latter, and the higher may be the transmitting speed. There exists a particular necessity for an increase of the latter in case the Morse key is not operated by hand but mechanically by means of a perforated tape.

Preferably, the increased voltage for an acceleration of the excitation and de-excitation may be supplied through a condenser. In this case, one can work with very high voltages without danger to the conductors and coils, owing to the energy stored in the condenser being almost consumed as soon as its object has been accomplished.

In the accompanying drawing:

Fig. 1 shows the connection diagram of one appropriate example of putting the invention into practice,

Fig. 2 shows, diagrammatically, the flow of current.

Fig. 3 shows a modification in a view similar to Fig. 1.

Referring to Fig. 1:—In the circuit of the antenna 2, a coil 32 is located and wound around a closed iron core 1, which, besides, carries a coil 30 and a coil 3. The coil 30 is connected with a high-frequency machine 31. A lever 5 serves for transmitting the Morse signals, said lever being held in its inoperative position (shown) by means of a spring 5^a, in which position it closes, by means of an insulated contact plate 33, the contacts 10, by means of which the condenser 8 is connected with the high-voltage source 9. Upon depression of the lever 5, it strikes upon a contact 7 and slides along the latter until it reaches in its end position also the contact 6. The fulcrum 49 of said lever is conductively connected with one end of the coil 3. The contact 7 is connected to one side of the condenser 8 and the contact 6 is connected to one pole of a continuous current source 4, the other pole of which is connected with the coil 3. From the same terminal of the coil 3 leads a conductor 34 over the ohmic resistance 35 to the other side of condenser 8.

An electromagnet 40 serves for operating the lever 5, one coil terminal of the former being connected through a conductor 36 with the current source 41. A conductor 37 leads from source 41 to a bracket 42, on

the upper end of which a contact roller 43 is located and conductively connected therewith. A second contact roller 44 is continuously pressed against the roller 43 by means of a spring 45. A conductor 38 leads from the electromagnet 40 to said spring 45 and thus to said contact roller 44. Between both said contact rollers runs a perforated tape 46, which is unwound from 10 a spool 47 and wound upon a spool 48 and which is adapted to normally prevent passage of current between rollers 43 and 44, unless a perforation therein appears between them, when such passage becomes possible.

15 The device works as follows:—The capacity in the circuit of the antenna 2 and its self-induction, of which the coil 32 with the magnetic circuit 1 forms an essential part, are so equalized that the natural frequency of the antenna circuit corresponds to the periodicity of the high-frequency machine 31, which is the case when the current of the continuous current source 4 flows through the coil 3. The antenna 2 is then 20 fully energized owing to the syntony between said frequencies. In the inoperative position of lever 5 shown, however, current does not flow through the coil 3. The iron of the magnetic circuit 1 is then not saturated, 25 the self-induction of the coil 32 is essentially increased, and the natural frequency of the antenna circuit 2 does not correspond to the periodicity of the high-frequency machine 31. The antenna does, therefore, take-up, 30 no energy. As soon as, then, by a rotation of the spool 48, the perforated tape 46 is set in motion and a perforation therein appears between the contact rollers 43 and 44, a current flows from the current source 35 over the conductor 37, the bracket 42, 35 the contact rollers 43 and 44, the conductor 38, the electromagnet 40, and the conductor 36, back to the current source 41. Consequently, the lever 5 is attracted, it closing 40 first the contact 7. Thereby, a rush of current flows from the condenser 8 through the resistance 35 and the conductor 34 into the coil 3 and hence through the fulcrum 49 of the lever 5, the latter itself, and the 45 contact 7, back to the condenser 8. The capacity of said condenser and its charging potential are so chosen that said rush of current suffices to produce the desired saturation in the iron core 1. At the moment 50 when the latter has been attained, also the lever 5 has reached the contact 6. Through the latter, the current source 4 is connected with the coil 3, and the former maintains 55 now the magnetization current in the coil 3. As described, due to the saturation of the iron core 1, the antenna 2 is tuned to resonance and takes-up full energy. As soon 60 as the perforated tape 46 interrupts again the contact between the contact rollers 43 and 44, the electromagnet 40 becomes cur-

rentless and the lever 5 returns to its inoperative position, it connecting then through the contact plate 33 the two contacts 10 and thus the high-voltage source 9 with the condenser 8, which is thus recharged. 70

The flow of the current through the continuous current coil 3 is represented by the full-line curve I in Fig. 2, the times being marked on the abscissa and the intensities 75 on the ordinate. As soon as the current supplied from the condenser 8 has attained its highest value of about 1 ampere, current is supplied from the battery 4, the intensity of which is represented by the horizontal 80 upper part of the curve I. The dotted part of the curve I shows, for sake of completeness, how the condenser current would flow if the circuit through the battery 4 would not be closed. The curve II shows, further, 85 the ascent of the current which would take place with a connection of the current source 4 to the coil 3 without the employment of a condenser. Whereas, in the latter case, the full magnetization current 90 would not yet be attained in 0.3 seconds, it is attained by the high voltage of the condenser in less than 0.003 seconds. The charging potential of the condenser is, in 95 this example, chosen 130 times as large as the voltage of the battery 4.

To prevent vibrations being produced in the circuit formed of the condenser 8 and the coil 3, the resistance 35, which has no self-induction, is inserted in said circuit. 100 In spite of the high voltage of the current source 9, the construction of the contacts 10 and 33 offers no difficulty, owing to their interruption taking place always in current-less condition only. 105

Instead of by the electromagnet 40, the lever 5 may also be operated by hand. Generally, the effect would then not be so complete, since a manipulatory depression cannot be so exact to the proper speed, so that 110 it might easily occur that the contact 6 is closed too late, e. g., the current source 4 is connected with the coil 3 when the magnetization current produced by the condenser 8 is already again decreased. The 115 Morse signals would then not be so sharp as when working with a perforated tape.

However, also with a telegraphing by hand the required period between the putting-in of the permanent current source 4 and that of the condenser can be exactly maintained with the employment of the diagram of connection shown in Fig. 3. In this example, also provision is made for a shortening of the de-excitation time. The 120 Morse key 13 is to be operated by the hand of a telegraphist. Upon depression of said key, current is sent from the battery 14 through the relay magnet 12, which actuates 125 a contact lever 11, the latter being coupled 130

by a rod 50 to the contact levers 51, 52, 53, 54. With currentless magnet 12, all said contact levers are kept in their inoperative position (shown) by means of springs 11^a, 51^a, 52^a, 53^a, 54^a, the contacts 15, 16, 20 and 21 being then closed. Upon attraction of the lever 11 by the magnet 12, the contacts last-mentioned are opened and the contacts 17, 19, 22, 23 and 24 are closed. The contacts 22 10 and 23 are reached by their levers 52 and 53 directly after starting of said movement, and the other contacts at the termination of said movement only. The fulcra of the contact levers 51 and 54 are connected with the two sides of a condenser 18. The electric connection of the latter leads on one side through the lever 54 and the contact 16 to one terminal 57 of the coil 3 and on the other side through the lever 51, the contact 15, and the ohmic resistance 35 to the other terminal 58 of said coil 3. The fulcra of the levers 52 and 53 are connected with the condenser 8. The electric connection of the latter leads on one side through the lever 53 and the contact 21 to one pole 59 of the high-voltage source 9 and on the other side through the lever 52 and the contact 20 to the other pole 60 of said high-voltage source 9. If, with excited magnet 12, the levers assume their operative positions, the condenser 18 is connected over the switch 54 and the contact 19 with the pole 60, and over the switch 51 and the contact 17 with the pole 59, of the current source 9, while the condenser 8 is connected over the switch 53 and the contact 23 with the terminal 57, and over the switch 52, the contact 22 and the ohmic resistance 35 with the terminal 58, of the coil 3, the lever 11 closing the contact 24 and connecting thus 20 the current source 4 with the coil 3.

The operation of the device last-described is as follows:-

As soon as the telegraphist intends to transmit a signal, he depresses the key 13. 45 Consequently, the magnet 12 is excited and contact levers 51—54 are moved downwards. Thereby, first the connections of the two condensers 8 and 18 are interrupted. Then, the condenser 8 is connected through the contacts 22 and 23 to the coil 3, the latter magnetizing thereby the iron core 1. As soon as the induction in the iron core has attained a certain value, the antenna 2 is tuned to resonance with the high-frequency machine 50 31 and takes-up full energy. The speed, with which the lever 11 is attracted, is so determined that at this moment also the contact levers have reached their end positions. Consequently, at this moment the current source 4 is connected over the contact 24 with the coil 3 and maintains here the magnetization current. Besides, the contact levers 51 and 54 connect the condenser 18 with the high-voltage source 9.

55 When the telegraphist releases the key 13, also the several contact levers return to their inoperative positions. Consequently, first the current source 4 is disconnected. The contact levers 52 and 53 slide, however, still a short time on the contacts 22 and 23, so that the connection of the coil 3 with the condenser 8 is still maintained. Thereby, part of the electric energy produced by the neutralization of the continuous current field is discharged into said condenser. When the contact levers reach their end positions, the condenser 18 is connected over the contacts 15 and 16 with the continuous current coil 3, but with a polarity opposite to that of the previously connected condenser 8. The capacity of the condenser 18 is so determined that its energy just suffices to neutralize, as quickly as possible, the continuous current field still existing in the iron core 1. Furthermore, the condenser 8 is connected over the contacts 20 and 21 with the high-voltage source 9 and thus re-charged by the latter. In this example, the ohmic resistance 35 prevents electric oscillations being produced between the condensers and the coil 3.

It is immaterial for the essence of the present invention whether the antenna is tuned with unexcited continuous current field or, as assumed in the connection diagrams shown, with a saturation of the iron core 1.

What I claim, is:-

1. Means for transmitting radio signals through an antenna, comprising an iron core having a coil, connected into the antenna circuit, a generator adapted to permanently supply radio frequency currents, a second coil on said iron core connected to said generator for supplying current to the antenna, a direct current coil on said iron core, means for supplying low potential direct current to said coil to vary the saturation of said core for tuning and detuning the antenna during the signaling operation, and a separate source of high potential direct current, and means for connecting it to said direct current coil for quickly raising the saturation of said core to the desired point before the low potential direct current supply is connected to said coil.

2. Means for transmitting radio signals through an antenna, comprising an iron core having a coil, connected into the antenna circuit, a generator adapted to permanently supply radio frequency currents, a second coil on said iron core connected to said generator for supplying current to the antenna, a direct current coil on said iron core, means for supplying low potential direct current to said coil to vary the saturation of said core for tuning and detuning the antenna during the signaling operation, and a condenser, a source of high potential direct current for charging said condenser and means for connecting the charged con-

denser to said direct current coil for quickly raising the saturation of said core to the desired point before the low potential direct current supply is connected to said coil.

3. Means for transmitting radio signals through an antenna, comprising an iron core having a coil, connected into the antenna circuit, a generator adapted to permanently supply radio frequency currents, a second coil on said iron core connected to said generator for supplying current to the antenna, a direct current coil on said iron core, means for supplying low potential direct current to said coil to vary the saturation of said

core for tuning and detuning the antenna 15 during the signaling operation, and a condenser, a source of high potential direct current for charging said condenser and means controlled by the low potential current supply means for connecting the charged condenser to said direct current coil for quickly raising the saturation of said core to the desired point before the low potential direct current supply is connected to said coil. 20

In testimony whereof I affix my signature. 25

HANS GERDIEN.
